No. 756,112.

PATENTED MAR. 29, 1904.

M. N. HALL & L. D. MOHLER.

CLOTHES DRAINER.

APPLICATION FILED JUNE 17, 1903.

NO MODEL.

UNITED STATES PATENT OFFICE.

MOURNIN N. HALL AND LEVI D. MOHLER, OF McPHERSON, KANSAS.

CLOTHES-DRAINER.

SPECIFICATION forming part of Letters Patent No. 756,112, dated March 29, 1904.

Application filed June 17, 1903. Serial No. 161,942. (No model.)

To all whom it may concern:

Be it known that we, MOURNIN N. HALL and LEVI D. MOHLER, citizens of the United States, residing at McPherson, in the county 5 of McPherson and State of Kansas, have invented certain new and useful Improvements in Clothes-Drainers, of which the following is a specification.

This invention aims to provide a draining-receptacle for use in connection with the ordinary clothes-boiler, and in its specific form embodies peculiar securing means disposed upon the said receptacle whereby the same may be readily applied and conveniently disposed upon the boiler, at the same time being adapted to be quickly removed.

For a full description of the invention and the merits thereof and also to acquire a knowledge of the details of construction of the 20 means for effecting the result reference is to be had to the following description and drawings hereto attached.

While the essential and characteristic features of the invention are susceptible of modification, still the preferred embodiment of the 25 invention is illustrated in the accompanying drawings, in which—

Figure 1 is a perspective view of a boiler, showing the lid thereof disposed transversely 30 in position for use as a draining-receptacle. Fig. 2 is a side elevation of the parts arranged as in Fig. 1. Fig. 3 is a perspective view of the lid, showing more clearly the engaging means thereon for holding same in position 35 when used as a drainer. Fig. 4 shows a modified form of engaging means for holding the drain-receptacle in position.

Corresponding and like parts are referred to in the following description and indicated 40 in all the views of the drawings by the same reference characters.

As premised hereinbefore, the invention is adapted for use upon the ordinary top of boiler 1 and also the usual form of lid 2. The 45 lid 2 is preferably of a conical form, being provided with a flange 3 upon its edges, which is received by the upper portion of the boiler when the lid is disposed so as to close the same. It is very desirable should the lid be 50 used as a drainer that the flange 3 be of in-

creased width, as shown by the dotted lines in Fig. 2 of the drawings, so that the lid may more readily hold the clothes. The boiler has a bead 4 at the edge of the opening therein, which is formed in the accustomed manner— 55 namely, by turning the material from which the boiler is made upon a continuous piece of wire which extends entirely about the edge thereof. Perforations or openings 5 are located upon a plate 10 upon the inner side of 60 the lid of the boiler in order to permit the water which drains from the clothes after having been disposed within the drainer-receptacle to pass back into the boiler. These openings are arranged at a somewhat intermediate 65 point between the ends of the drainer-receptacle and are provided both upon the body of the lid and upon the flange 3 thereof. When the lid is used as a drainer, the same is disposed transversely of the boiler, as most clearly 70 shown in Fig. 1 of the drawings, and in order to secure the lid in the position illustrated engaging means are provided. These engaging means consist, preferably, of a series of 75 hooks 6, disposed at intervals upon the upper side of the lid and longitudinally thereof. These hooks are adapted to engage the bead 4 upon one side of the boiler, and a latch device is provided upon the opposite portion of the upper side of the lid to coöperate 80 with the hook 6 to secure the lid by engagement with the bead 4 upon the opposite side of the boiler. The latch device mentioned consists of a U-shaped engaging member 7, which member 7 is rigidly secured in place. 85 Pivoted to the lid in any suitable manner is a lever 8, which is provided at one end with an eccentric cam 9, which cam engages beneath the bead 4 when the lever 8 is manipulated in a proper direction. The cam en- 90 gages not only beneath the bead 4, but clamps a portion of the body of the boiler between the U-shaped member 7 and itself. By this means the lid for same being used as the draining-receptacle is rigidly held in position 95 by positive lock means and is adapted to sustain all reasonable weight to which it may be subjected, usually merely the weight of the clothes which are lifted from the boiler thereinto.

The modified form of securing means is illustrated in Fig. 4, consisting simply in providing a series of hooks similar to the series 6 before described instead of the latch means.

- 5 The purpose in having a plurality of hooks is obvious, being to adapt the lid or draining receptacle for application to different sizes of receptacle. The hook 6 may be rigidly affixed to the lid by any means found most suitable.
- 10 The conical form of the lid causes same to rest in an inclined position, and this is very advantageous, since drained water concentrates toward the openings 5 in the receptacle.

In using the modified form of engaging means (shown in Fig. 4) it is necessary that the corresponding hooks adjacent the ends of the receptacle be engaged beneath the body 4 by a longitudinal movement of the said receptacle, with the said hooks disposed so that 20 as the receptacle is moved toward the central portion of the boiler the said hooks will ride beneath the bead.

The invention is extremely simple. The draining-receptacle may be disposed very conveniently, so that the clothes may be lifted directly from the boiler into the same, which is of especial importance.

Having thus described the invention, what is claimed as new is—

- 30 1. The combination with a holding-receptacle, of a drainer-receptacle, engaging means disposed adjacent one end of the drainer-receptacle, other engaging means comprising a U-shaped engaging member disposed upon 35 the opposite end portion of the drainer-re-

ceptacle, and a cam-lever pivoted to the U-shaped engaging member aforesaid for co-operation therewith to positively lock the drainer-receptacle to the holding-receptacle.

- 2. The combination with a holding-receptacle, of a drainer-receptacle, engaging means disposed adjacent one end of the drainer-receptacle, engaging means disposed adjacent the opposite end of the drainer-receptacle, and lock means coöperating with the latter-mentioned engaging means for positively securing the same in engagement with the holding-receptacle.

3. In a drainer for clothes, the combination with a holding-receptacle having bead thereon, a drainer-receptacle of conical form disposed upon the said boiler and provided with openings, a series of hooks disposed adjacent one end of the said receptacle and adapted for engagement with the bead upon one side 55 of the holding-receptacle, a U-shaped engaging member disposed upon the opposite end portion of the receptacle and adapted to engage the bead upon the opposite side of the holding-receptacle, and an eccentric cam 60 adapted to coöperate with the U-shaped member to positively lock the drainer-receptacle in position upon the holding-receptacle.

In testimony whereof we affix our signatures in presence of two witnesses.

MOURNIN N. HALL. [L. S.]
LEVI D. MOHLER.
